APPARATUS FOR DRYING PAPER CUPS

Vincent E. Heywood, Worcester, Mass., assignor
to United States Envelope Company, Spring-
field, Mass., a corporation of Maine

Application March 24, 1931. Serial No. 525,017

8 Claims. (Cl. 93—50)

The present invention relates to the manufacture of round paper drinking cups of the type consisting of a tubular body portion, within which is assembled a separate bottom of circular disk form. In the making of such cups, the edges of the blanks for the body portions are brought into over-lapping engagement by a curling or wrapping operation to enclose the bottom disks, with a seam extending longitudinally of each cup body, and the object of this invention is to provide means for thoroughly drying the adhesive extending along the cup body seams while the cups are in process of manufacture.

In my copending application, Serial No. 265,136, filed jointly with Ralph D. Hoaglund on March 28, 1928, there is shown and described a machine for making round cups of the above described type, and for purposes of illustration, the apparatus of the present invention is shown as cooperating with certain parts of the machine shown in the above mentioned application. Briefly stated, the cup machine referred to above consists of a rotatable turret providing a number of separate stations at which various operations are successively performed on assembled body blanks and bottom disks, which operations result in the production of round cups each having a longitudinal seam extending along the overlying edges of the body blank, with a bottom disk secured within the surrounding tubular body. The turret on which the cups are thus formed operates with a step-by-step movement and each step of the turret is accompanied by the discharge of a substantially completed cup from the turret, either for the performance of additional operations thereon, such as rim spinning, or for transmission of the cup to a suitable receiving device for stacking the cups in nesting relation.

In case it is desired to spin the open rims of the cups, it is essential that the longitudinal seams of the cup bodies be thoroughly dried before removing the cups from the forming turret, and the present invention provides means for insuring this result. As will hereinafter more fully appear, one embodiment of the invention provides apparatus cooperating with the cup forming turret in such a manner that each cup is removed from the turret at one station and returned thereto at another station, with the interval between the transfers of each cup of such long duration that the longitudinal seam of each cup is thoroughly dry. Since each cup is returned to the turret after drying, there is no interruption in the normal functioning of the

turret, or any of the mechanisms associated therewith, the net result being equivalent to the provision of a forming turret having an almost infinite number of drying stations in which no operations are performed on the cups. Other 60 advantageous features of the invention are set forth more fully hereinafter, reference being had to the accompanying drawings, in which:—

Fig. 1 is a view in front elevation of a portion of a cup forming machine with the improved 65 drying apparatus of the present invention cooperating therewith.

Fig. 2 is a fragmentary view showing, on an enlarged scale, a portion of the parts shown in Fig. 1, as viewed from the opposite side. 70

Fig. 3 is a view in side elevation of the parts shown in Fig. 2, portions being shown in section to illustrate details of construction.

Fig. 4 is a fragmentary view partly in section illustrating the transferal of a cup from the 75 forming turret to the drying apparatus.

Fig. 5 is a fragmentary view illustrating a modified form of drying apparatus.

Like reference characters refer to like parts in the different figures. 80

Referring first to Fig. 1, the cup forming machine with which the drying apparatus cooperates generally comprises a main turret 1 providing around its periphery a plurality of equally spaced cup forming mandrels 2, the whole turret 85 1 being adapted to rotate with a step-by-step movement about the axis of a central shaft 3. The mechanism for rotatably driving the turret 1 is such that for each step of the turret it is turned through an angle corresponding to the 90 angular displacement between adjacent mandrels 2, with a dwell between each step. As fully set forth and described in the aforesaid copending application, Serial No. 265,368, each dwell of the turret 1 is accompanied by the performance of 95 certain cup forming operations at different mandrels 2 which finally result in the production of a cup comprising a tapered body portion 4 wrapped in surrounding relation to a bottom disk 5 closing the smaller end of the body 4, as shown in section 100 in Fig. 3. As shown on the cups carried by the mandrels 2 below the mandrel shown in section in Fig. 3, each cup body provides a longitudinal seam 4a extending along the overlapped edges of the body 4, and it is one purpose of the apparatus 105 of the present invention to automatically remove a cup from one mandrel 2 of the main turret and return it to another mandrel after the lapse of an interval more than sufficient for thorough drying of the gum or paste along the seam 4a. 110

However, before proceeding with a detailed consideration of the construction and operation of the drying apparatus, there will be briefly described the means for handling a cup after its removal from the main turret 1 for the purpose of performing either an additional operation thereon, such as rim spinning, or for delivering it in nesting relation to a suitable container. As best shown in Figs. 2 and 3, the main turret 1 cooperates with a secondary turret 6 mounted on a shaft 7 parallel to the main turret shaft 3. This secondary turret 6 provides a number of spaced hollow seats, or receptacles 8 of such form as to receive the bodies 4 of cups small end first, and gearing 9 between the turrets 1 and 6 serves to drive the secondary turret 6 with a step-by-step movement adapted to axially align a seat 8 with a mandrel 2 at each step. One of the seats 8 of the secondary turret 6 is shown in Fig. 3 as being 10 in alinement with a mandrel 2 having a cup thereon, and as will hereinafter appear, the transferal of a dried cup, closed end first, from a mandrel 2 to a seat 8 takes place in the dwell of both turrets 1 and 6 following each step. And as previously pointed out, the drying apparatus which 20 comprises the present invention cooperates with the main turret 1 in such a manner that both the transferal of a cup from the main turret to the drying apparatus and the return of a cup from 30 the drying apparatus to the main turret also takes place in the dwell of the turrets, as will now be described.

As best shown in Fig. 3, the frame 10 which carries the bearing for the secondary turret shaft 7 provides an upwardly extending portion 10a terminating in an elongated bearing 11 for a shaft 12. The shaft 12 projects at both ends beyond the bearing 11 with its outer end carrying a sprocket wheel 13 connected by a chain 14 to a sprocket wheel 15 mounted on a shaft 16 driven through a chain 17 and sprockets 17a and 17b from the main drive shaft 18 of the cup machine indicated in Fig. 2. The other end of the shaft 12 carries a sprocket wheel 19 which, as best shown in Fig. 40 2, serves to drive the conveyor chain 20 of the drying apparatus. The conveyor chain 20 carries a large number of spaced cup receiving rings 21, each ring 21 being of such diameter as to freely receive a cup body 4, closed end first, without permitting the larger open end of the cup to pass therethrough, as clearly shown in Fig. 4. The rings 21 have their centers spaced apart such a distance that when one ring 21 is in alinement with the mandrel 2 shown in section in Fig. 3, the ring next below will also be in alinement with the mandrel shown as being empty in Fig. 3. This essential relation is shown in dotted lines in Fig. 2 and the ratio of the sprockets 17a and 17b through which the chain 14 is driven from the main shaft 18 is such that the turning of the main turret 1 through one step is accompanied by slow movement of the chain 20 through a distance equal to the displacement between centers of adjacent rings 21. Therefore, each time the turret 1 dwells in its movement, the mandrel 2 shown in section in Fig. 3, as well as the mandrel below it, have their respective axes alined with the centers of two adjacent rings 21 long enough for the transfer of cups from the turret 1 to the chain 20 and 70 from the chain 20 back to the turret 1, as will be hereinafter described.

As best shown in Fig. 1, the chain 20 extends upwardly from one side of the driving sprocket wheel 19 around a guide wheel 22 rotatably supported a considerable distance above the cup

machine by suitable hanger 23. The chain 20 then extends horizontally to a second guide wheel 24 rotatably supported by a hanger 25 from which it passes downwardly toward the turret 1, as indicated by the arrows. For the purpose of guiding the chain 20 so that its rings 21 will be accurately positioned in register with mandrels 2 of the turret 1, a pair of guide rolls 26 and 27 are provided, which as best shown in Fig. 2, are supported by studs 28 extending from the frame portion 11. Thus the chain 20 is constrained to follow the course shown in Fig. 2, with two of its rings 21 positioned in alinement with two of the turret mandrels 2 at each dwell of the turret 1. The rings 21 are incorporated in the chain 20 in such a manner that the chain can be readily assembled from standard sprocket chain parts, this construction being illustrated in the broken away portion of the chain at the right of Fig. 2. As shown, each ring 21 is welded or otherwise formed integrally with a solid bar 29 provided with openings 30 at its ends for receiving suitable pins pivotally connecting the bar 29 to the side links 31. In other words, each bar 29 carrying a cup ring 21 is similar in all other respects 100 to the remaining bars 29a of the chain 20, so that the chain may be readily assembled and rings 21 removed and replaced, as desired.

Referring now to Fig. 3, it will be seen that each main turret mandrel 2 provides a longitudinal opening 32 in which is slidably received a plunger 33 carrying a circular head 34, having a diameter slightly less than the diameter of the bottom disk 5 of a cup. The other end of the plunger 33 projects rearwardly through the web 110 1a of the turret 1, and is surrounded by a spring 35 which normally tends to hold the head 34 in retracted position within the cup, in engagement with the end of the mandrel 2. In this retracted position, the head 34 is spaced somewhat from 115 the bottom disk 5 and this is the position occupied by the parts when a mandrel 2 comes to rest with a cup thereon in axial alinement with a stationary ring 21 of the conveyor chain 20. As the mandrel 2 comes to rest, as shown in Fig. 3, a shoulder 36 120 on the rear end of the plunger 33, against which bears the spring 35, comes into register with a then stationary plunger 37 slidably mounted in a bracket 38. The other end of the plunger 37 which extends beyond the bracket 38 is 125 pivotally connected to a lever arm 39 mounted on a shaft 40 supported by a bracket 41, best shown in Fig. 2. The other end of the shaft 40 carries a second lever arm 42, turnable with the arm 39, to which is pivotally 130 connected the upper end of a link 43. The lower end of the link 43 is connected to a lever arm 44 mounted on a rock shaft 45 by means of a pin 46 which also carries a roll 47. The roll 47 bears on the surface of a cam 48 mounted on a shaft 49, 135 driven from the main shaft 18, only a portion of which is shown in Fig. 2.

Rotation of the cam shaft 49 causes the cam 48 to impart a longitudinal movement to the plunger 37 in the direction of the turret 1, and since this plunger 37 is in engagement with the end of the mandrel plunger 33, the head 34 is moved in the direction of the cup bottom disk 5. The movement of the plunger 37 is so controlled that the head 34 will engage the bottom disk 5 and cause 145 the whole cup to be loosened from the mandrel 2. As the plunger 37 moves to the limit of its stroke for the cup loosening operation, a port 50 extending radially from a longitudinal passage 51 in the plunger comes into register with an open- 150

ing in a pipe 52 see Fig. 2 which is adapted to be supplied with air under pressure. As indicated in dotted lines in Fig. 4, the passage 51 of plunger 37 is in alinement with a passage 53 extending 5 through the mandrel plunger 33, so that when the port 50 registers with the pressure pipe 52 a blast of air is delivered through the head 34. This blast of air striking the solid bottom disk 5 of the already loosened cup causes the immediate 10 transfer of the cup from the mandrel 2 into the alined ring 21 and is shown as having taken place in Fig. 4.

As previously pointed out, a dwell takes place in the movement of the main turret 1 after each 15 step thereof, and the cam 48 is so timed that the transferal of a cup from a mandrel 2 into a ring 21 takes place shortly after the turret comes to rest. Therefore, by the time the turret 1 is turned through another step the chain 20 has 20 already shifted the cup just transferred away from the empty mandrel and has moved an empty ring 21 into position with the mandrel carrying the next cup. At the time of the transfer of a cup into a ring 21, seam 4a of the cup body 4 is still more or less moist, so that the rigid ring 21 holds this seam against any spreading as the ring 21 starts to traverse the whole length of the chain. It is evident from a consideration 25 of Fig. 1 that the chain 20 presents an extremely large number of rings, as compared to the number 30 of cup forming mandrels 2 on the turret 1, and since the chain 20 travels through only the space of one ring for each mandrel step, the turret 1 will make several revolutions while a given cup 35 is passing around the chain. Consequently, the cup will be thoroughly dried by the time it reaches the roll 27 in register with an empty mandrel 2 of the turret 1, as indicated in Fig. 3 below the mandrel shown in section, whereupon instrumen- 40 talities come into action to transfer a dried cup from a ring 21 onto the empty mandrel, simultaneously with the transfer of an undried cup from a mandrel to a ring, as previously described.

As best shown in Fig. 3, the frame portion 10a 45 carries a finger 54 providing an inclined portion 55 which is disposed in the path of movement of a cup bottom as the latter is carried into alinement with the empty mandrel 2 by its ring 21. As indicated by the cup shown in dotted lines, the 50 inclined portion 55 is so positioned that the rim of a cup bottom strikes it while the cup is still fully inserted within a ring; therefore the fixed inclined portion 55 exerts a wedging action on the cup as the latter is moved by the chain into 55 register with the empty mandrel 2. This has the effect of shifting the cup bodily, open end first, within the ring as indicated in full lines in Fig. 3, thereby loosening the larger portion of the cup from the grip of the ring slightly ahead of a 60 blast of air delivered against the bottom disk 5 by means of a nozzle 56 in alinement with the axis of the empty mandrel 2, thereby transferring the previously loosened cup from the ring 21 onto the empty mandrel where it tends to remain by reason of the wedging action of the mandrel with the tapering walls of the cup body. The nozzle 56 is adapted to be supplied with air under pressure through a pipe 57, and in Fig. 1 there is indicated diagrammatically the manner in which 65 the nozzle 56 may be caused to deliver a jet of air just as a ring 21 with a loosened cup thereon alines with the nozzle 56.

As previously pointed out, the pipe 52 which leads to the plunger 37 is connected to a suitable source of air pressure, and this source 70

is represented in Fig. 1 as comprising a pipe 58 supplied from the usual air pressure line provided in cup making establishments. This pipe 58 is adapted to supply air under pressure to a suitable distributing manifold 60 into which lead both the 80 pipe 52 and the pipe 57 from the nozzle 56. In order to insure that an air blast will be delivered by the nozzle 56 at the moment a ring 21 moves a cup into register with an empty turret mandrel 2, the manifold 60 provides a sliding valve 85 member 61 providing a port 62 normally held out of register with a port 63 of the manifold, and the entrance to the pipe 57. One way of holding the port 63 closed consists of a cam 64 mounted on a continuously driven shaft 65 connected to 90 the drive shaft 18, the cam bearing on a roll 66 carried by the valve 61. The cam 64 provides a depression 67 and when the roll 66 is received therein, the valve 61 is moved against the pressure of a spring 68 to open the port 63, thereby 95 admitting a blast of air under pressure to the nozzle 56. Since the remainder of the cam 64 is concentric about the axis of the shaft 65, the blast of air at the nozzle 56 is shut off as soon as the cup has been transferred to the empty 100 mandrel 2. Since the shaft 65 operates the valve 61 once for each step of the turret 1, it follows that each time the main turret 1 comes to rest with its empty mandrel 2 in alinement with the nozzle 56, and the travel of the chain 20 moves 105 a loosened dried cup into register with the mandrel, the nozzle 56 will deliver a sudden strong blast of air which conveys the cup open end first to the empty mandrel 2. Subsequent steps of the main turret 1 then carry the dried cup to another 110 station, at which it may be discharged from the main turret in any suitable manner for the performance of additional operations thereon, such as rim spinning, or for delivery to a suitable receptacle for completed cups. 115

As illustrative of the manner in which a dried cup can be removed from the main turret, there is shown in Fig. 3 an arrangement for loosening a dried cup from a mandrel 2 and transferring it to the secondary turret 6 by an air blast, in 120 substantially the same manner as described with reference to the means for transferring a cup from the turret 1 to the chain 20. This transfer means consists of a plunger 69 that is adapted to cooperate with the shoulder 36 of an alined 125 mandrel plunger 33 in the same manner as described with reference to the plunger 37. The plunger 69 is pivotally connected to an arm 70 on the same shaft 45 which carries the arm 44; consequently, the plungers 37 and 69 operate in 130 unison to first loosen a cup from a mandrel and then discharge it from the mandrel by means of an air blast. As shown, the operation of the plunger 69 is adapted to cause the delivery of a dried cup to one of the seats 8 of the secondary 135 turret 6, movement of which serves to clear the cup from the main turret, as indicated in Fig. 2. When a dried cup has been thus cleared from the main turret 1 by movement of the secondary turret in step with the main turret, the cup is 140 held in its seat 8, either for the performance of a rim spinning operation, or for its delivery open end first from the seat 8 to a suitable receptacle for receiving finished cups in nesting relation.

As indicated in Fig. 3, the operations of rim 145 spinning and crimping on a cup in a seat 8 of the secondary turret may be suitably formed by means of a rotatably driven rim spinner 71 and a rim crimping head 72 adapted to cooperate with a crimping ring 73 surrounding each seat 150

8. The construction and functioning of the rim spinning and crimping instrumentalities are fully set forth in my aforesaid copending application, Serial No. 265,368 and need not be described in detail herein. It is sufficient for an understanding of the purpose of the present invention to state that the rim spinner 71 operates on the open rim of a cup received in the seat 8 just below the seat to which a dried cup is delivered from the main turret 1, and by reason of its combined rotative and axial movement, the spinner curls over the rim of the cup. Since the longitudinal seam of the cup has been thoroughly dried in traversing the drier chain, the rim spinning operation is effectively performed without any tendency of the wall of the cup to crumple at the seam.

Since the secondary turret 6 is driven in step with the main turret 1, the dried cups delivered to the secondary turret are successively operated upon by the rim spinner 71 during each dwell of the turrets, and the crimping head 72 cooperates with the crimping ring 73 of each seat when a rim spun cup reaches the secondary turret position diametrically opposite the transfer position. The cooperation between the crimping head 72 and the crimping ring 73 serves to strengthen the previously spun rim and the next step of the secondary turret 6 carries the completed cup to the station in the same horizontal plane with the transfer station, as viewed in Fig. 2. At this final station of the secondary turret, the seat 8 carrying the completed cup is in alinement with a delivery chute 74, only a portion of which is shown in Fig. 3. The chute 74 consists of a number of guide bars 74a which are spaced apart far enough to freely receive a finished cup when it is delivered open end first into the chute by a blast of air delivered against the cup bottom while in the seat 8. The construction of the secondary turret casting whereby a blast of air is delivered at the bottom of each seat 8 when it registers with the chute 74, is fully described in the aforesaid copending application, Serial No. 265,368, and as indicated diagrammatically in Fig. 1, the pipe 57 which supplies the chain transfer nozzle 56 also supplies the secondary turret with air under pressure through a branch pipe 57a leading to the center of the secondary turret casting. Therefore, the delivery of a finished cup from the secondary turret 6 to the chute 74 occurs each time a dried cup is transferred from the chain 20 to the main turret 1, the cups arranging themselves in nesting relation in the chute so as to build up a stack as successive cups are delivered open end first from the secondary turret.

Referring now to Fig. 5, there is shown a modification of the invention which briefly stated, consists in delivering dried cups from the conveyor chain directly to a delivery chute for stacking in nesting relation, without performing any operations on the rims of the dried cups. In this modified arrangement, provision is also made for driving the conveyor chain from the cup forming turret so that the cup drying rings have a step-by-step movement synchronized with the turret movement, so that each ring is accurately alined with a turret mandrel at the moment of transfer from the mandrel to the ring.

Referring to Fig. 5, the turret 1 is constructed and operated in exactly the same manner as the turret shown in Fig. 1, so that its mandrels 2 present formed cups successively to the rings 21 of a chain 20, only a portion of which is shown.

The chain 20 is constructed in exactly the same manner as the chain previously described with reference to Fig. 2, and is driven by means of a sprocket wheel 19a mounted on a shaft 12a extending parallel to the turret shaft 3. The shaft 12a is driven from a counter shaft 75 through a chain 76 passing around sprocket wheels 77 mounted on the shafts 12a and 75 respectively, the wheels 77 being of the same diameter with the same number of teeth. The shaft 75 also carries a gear 78, the teeth of which are in mesh with gear teeth 79 provided around the periphery of the turret 1, so that intermittent rotative movement is imparted to the shaft 75 through the step-by-step movement of the turret 1.

As previously pointed out, the turret 1 at each step turns through an angle determined by the displacement between mandrels 2, and the number of teeth on the gear 78 is such that each step of the turret 1 is adapted to turn the shaft 75 through one-third of a complete revolution. Consequently, the shaft 12a is turned through the same angle upon each step of the turret 1, and since the number of teeth on the driving sprocket 19a is three times the number of chain links between adjacent rings 21, the chain is moved in exact synchronism with the turret. That is to say, each step of the turret 1 will be accompanied by corresponding movement of the chain so that a ring 21 will come to rest at the guide roll 26a in exact axial alinement with a mandrel carrying a cup.

The transfer of a cup from a mandrel 2 to a ring 21 positioned at the roll 26a is accomplished in exactly the same manner as described with reference to Figs. 3 and 4, each cup so transferred being carried away from the turret 1 by the chain 20 in the direction of the arrow in Fig. 5. After a cup carried by a ring 21 has traversed nearly the entire course of the chain, it finally reaches a position just above the driving sprocket wheel 19a in which it comes to rest in alinement with the open end of a chute 80 similar in construction to the chute 74 previously referred to. For purposes of illustration, the chute 80 is shown as having been turned at an angle to the axis of the turret 1, and cups from the conveyor rings 21 are adapted to be delivered open end first into the chute 80 by means of an air blast delivered through a pipe 81. Admission of air under pressure to the pipe 81 is controlled in timed relation to the intermittent movement of the turret 1 in the same manner as described with reference to the pipe 57 in Fig. 1, so that the successive delivery of dried cups, open end first, to the chute 80 results in the formation of a stack of cups in nesting relation, as indicated. Since each cup is rigidly held within a ring while passing around the drier chain 20, there is no possibility of the seams spreading during the drying period; consequently, the dried cups are nested uniformly in the delivery chute 80 in condition for packing.

From the foregoing, it is apparent that by the present invention there is provided an improved apparatus for drying round cups in process of manufacture, the apparatus functioning simultaneously with the cup forming means, so that completely dried cups are delivered at the same rate that the cups are formed. As a result of the functioning of the drying apparatus, it is possible to deliver completely dried cups for the performance of other operations thereon, such as rim spinning, or to deliver the dried cups one by one to a suitable receptacle for stacking in nest-

ing relation. In either event, the drying of the cups is so complete that any crumpling or spreading of the cup body seams is entirely eliminated.

I claim,

- 5 1. In apparatus of the class described, the combination with a rotatable turret providing a plurality of angularly spaced cup forming mandrels, and means for imparting a step-by-step turning movement to said turret, of a conveyor carrying a plurality of cup receiving rings spaced apart the same distance as said turret mandrels, means for moving said conveyor to cause axial alinement of adjacent rings with adjacent turret mandrels during a dwell of the turret, and means 10 for simultaneously bringing about the transfer of a cup from a mandrel to a ring and the transfer of another cup from a ring to a mandrel.
2. In apparatus of the class described, the combination with a rotatable turret providing a plurality of angularly spaced cup forming mandrels for internally supporting conical cup bodies and means for imparting turning movement to said turret, of a continuously moving conveyor carrying a plurality of spaced cup receiving rings for externally supporting conical cup bodies and means for transferring a cup, small end first, from a mandrel to a ring when a ring is in approximate alinement with a mandrel.

3. In apparatus of the class described, the combination with a rotatable turret providing a plurality of angularly spaced cup forming mandrels for internally supporting conical cup bodies and means for imparting turning movement to said turret, of a conveyor carrying a plurality of cup receiving rings for externally supporting conical cup bodies spaced apart the same distance as said turret mandrels, means for continuously moving said conveyor at such a rate as to bring a ring into alinement with a mandrel, and means for transferring a cup, small end first, from a mandrel to a ring at the moment of approximate alinement of a ring with a mandrel.

4. In apparatus of the class described, the combination with a rotatable turret providing a plurality of mandrels for internally supporting cup bodies having closed ends, and means for imparting a step by step turning movement to said turret, of a conveyor carrying a multiplicity of spaced rings greatly in excess of the number of said mandrels, said conveyor being driven in timed relation with said turret, and means for transferring cups one by one, closed end first, from the mandrels of said turret to the individual rings of said conveyor, with the body of each cup externally supported by a conveyor ring.

5. In apparatus of the class described, the combination with a rotatable turret providing a plu-

rality of mandrels for internally supporting cup bodies having closed ends, and means for imparting a step by step turning movement to said turret, of a conveyor carrying a multiplicity of spaced rings greatly in excess of the number of said mandrels, said conveyor being driven in timed relation with said turret, and means cooperating with each mandrel when it is in register with a ring of said conveyor for transferring a cup, closed end first from the mandrel to a ring, with the cup body externally supported by said ring.

6. In apparatus of the class described, the combination with a rotatable turret providing a plurality of mandrels for internally supporting cup bodies having closed ends, and means for imparting a step by step turning movement to said turret, of a conveyor carrying a multiplicity of spaced rings greatly in excess of the number of said mandrels, said conveyor being driven in timed relation with said turret, and means cooperating with a mandrel when in register with a conveyor ring for delivering a blast of air against the closed end of the cup on said mandrel for projecting said cup closed end first to said ring, with the cup body externally supported by said ring.

7. In apparatus of the class described, the combination with a rotatable turret providing a plurality of mandrels for internally supporting cup bodies having closed ends, and means for imparting a step by step turning movement to said turret, of a conveyor carrying spaced rings driven in timed relation with said turret, with said rings spaced apart the same distance as said turret mandrels to cause axial alinement of adjacent rings with adjacent mandrels during a dwell of the turret, and means for simultaneously bringing about the transfer of a cup closed end first from a mandrel to a ring, and the transfer of another cup open end first from a ring to a mandrel.

8. In apparatus of the class described, the combination with means for forming round cups each having a tapered body with a longitudinal seam secured by adhesive, means for spinning the open rims of said formed cups, and a conveyor providing a multiplicity of spaced rings each having a diameter intermediate the largest and smallest diameters of a cup body, of means for removing cups one by one, small end first, from said forming means for reception in said conveyor rings, and means for driving said conveyor with a slow measured movement to carry said cups while externally supported in said rings to said rim spinning means for the purpose of drying the body seams of said cups in transit.
